UNITED STATES PATENT OFFICE.

EVERETT P. ADAMS, OF GREENTOP, MISSOURI.

DOOR-HANGER.

1,058,513.

Specification of Letters Patent.

Patented Apr. 8, 1913.

Application filed August 28, 1912. Serial No. 717,562.

To all whom it may concern:

Be it known that I, EVERETT P. ADAMS, a citizen of the United States, residing at Greentop, in the county of Schuyler and State of Missouri, have invented new and useful Improvements in Door-Hangers, of which the following is a specification.

The general object of this invention is the provision of a door hanger particularly adapted for use in connection with the sliding doors used in railroad rolling stock, said hanger being so constructed as to facilitate the opening and closing of the door, and to this end the invention consists in certain constructions, arrangements and combinations of devices which will be described hereinafter and then pointed out in the appended claim.

In carrying out the object of the invention generally stated above, it will be understood, of course, that the essential features thereof are susceptible to changes in details and structural arrangements, one preferred and practical embodiment being shown in the accompanying drawings, wherein:

Figure 1 is a fragmentary side elevation of a freight car, showing the hanger applied thereto and constructed in accordance with the invention. Fig. 2 is a vertical longitudinal sectional view. Fig. 3 is a transverse section. Fig. 4 is a detail perspective view of one of the door supports used in connection with the invention.

Referring more particularly to the accompanying drawings in which like reference characters designate similar parts, *a* indicates a car of any well known construction having the door opening 5 therein adapted to be closed by the door 6 which is supported in a manner which will presently appear.

Extending longitudinally of and above the door opening 5 is a track casing or housing 7 which is of rectangular formation and which is secured to the side of a car *a* in any preferred manner. Secured to the vertical side of the housing 7 adjacent the lower end thereof and extending longitudinally of said housing are the parallel tracks 8 which are spaced to provide a longitudinal slot 9 for the reception of a portion of the hereinafter described device designed to be connected to the door 6. The housing 7 is provided with a closed end 10 and an opened end 11 which

is adapted to be closed by means of a detachable door 12 provided upon its inner surface 55 with the alined staples 13 which are adapted to receive the locking pin 14 which is passed through alined transverse openings formed in the vertical sides of the said housing.

The door 6 has secured to its upper edge 60 a plurality of supports *b* which are preferably formed from a single length of material to provide the door engaging members 15 which are secured to the door by means of the fasteners 16. Each of the supports is 65 contracted intermediate the ends thereof to provide shoulders 17 adapted for engagement with the top edge of the door and the remaining portions 18 of the support *b* are adapted to receive therebetween a spacing 70 block 19, said portions 18 and block 19 being provided with alined transverse openings adapted to receive the transverse axle 20 which projects beyond each side of the portions 18. Each of the axles 20 is adapted to 75 receive thereon on each side of the portions 18 a grooved wheel 21, all of said wheels being adapted to engage the tracks 8 when the door is being supported by the housing.

It will be seen, by the provision of the 80 particular form of housing, that the hanger is amply projected against the elements such as snow and rain and that there will be no danger of the tracks becoming clogged, thus obviating the possibility of 85 the door being prevented from working smoothly at all times. It will also be seen that by removing the door 12 of the housing 7, access may be had to the parts of the hanger within said housing whereby the 90 same may be repaired or replaced as may be desired.

From the foregoing description taken in connection with the accompanying drawings, it will be seen that the invention contemplates providing a door hanger which is 95 simple in construction, thus reducing the cost of manufacture of the same to a minimum, and which is durable and effective in carrying out the purpose for which it is 100 designed.

What is claimed is:

A door hanger for cars including a housing secured above the door opening, tracks carried by the housing and door supports 105 movably mounted in the housing, said sup-

ports each constructed of a single length of material terminally formed to provide spaced leaves at one end to embrace each side of the door and vertically extending upper sections spaced apart a distance less than the leaves, a spacing block arranged between the upper sections and wheel shaft projecting through said sections and block,

and wheels carried on the shaft to cooperate with the tracks of the hanger.

In testimony whereof I affix my signature in presence of two witnesses.

EVERETT P. ADAMS.

Witnesses:

J. W. BRADLEY,
P. A. ADAMS.
